UNITED STATES PATENT OFFICE.

ALBERT C. MEYER, OF SAN DIEGO, CALIFORNIA.

ELECTRIC SIGN.

1,069,627.

Specification of Letters Patent.

Patented Aug. 5, 1913.

Application filed February 7, 1912. Serial No. 675,923.

To all whom it may concern:

Be it known that I, ALBERT C. MEYER, a citizen of the United States, and a resident of San Diego, in the county of San Diego and State of California, have invented certain new and useful Improvements in Electric Signs, of which the following is a specification.

My invention relates to improvements in electric signs, and more particularly to be used for advertising purposes, and in which the sign characters are intermittently altered by electrically operated means.

The objects of my invention are, first to provide an electrically operated sign in which the advertising matter may be easily and readily changed by any person, second, to provide such a sign which is simple, durable, easily constructed and easily installed, third, to provide a sign in which several different words or sentences may be intermittently shown by the use of one line of characters, and fourth, to provide means for confining the light in the immediate vicinity of each individual lamp.

With these and other objects in view, as will appear, my invention consists of certain novel features of construction, combination and arrangement of parts, as will be herein-after described in detail and particularly set forth in the appended claims, reference being had to the accompanying drawings and to the characters of reference thereon, which form a part of this specification, in which:

Figure 1 is a diagrammatic view of my electric sign showing a portion of the wiring and operating means in connection therewith, in which the repetition of the wiring and contact points has been omitted for the sake of simplicity, Fig. 2 is an elevational view of one of the operating units, Fig. 3 is a plan view thereof, showing parts broken away and in section, Fig. 4 is a perspective view of a portion of the character block frame, showing one of the character block units in position, Fig. 5 is a section through A—B in Fig. 2 of the character block frame and holder therefor, Fig. 6 is a perspective view of one of the spring contacts, Fig. 7 is a sectional view of a portion of the sign board, showing the shrouding enveloping the lamps.

Similar characters of reference refer to similar parts throughout the several views.

The sign board 1 is provided with a series of incandescent lamps 1^a, and each lamp is

enveloped by a shroud 1^b as shown in Fig. 7, so that the light rays from any one lamp will not be intercepted by the surrounding lamps. The form controlled switch board 2 is provided with a plurality of units, one of which is shown in detail in Fig. 2. The hanger arms 5 are pivotally mounted on brackets 5^b, which are rigidly mounted on form controlled switch board 2. The cross bars 9 extend along the board 2 and are pivotally mounted at each of their ends on one of the hanger arms 5, and the holes in the bars 9, where they are pivoted to the arm 5, are oblong thereby allowing the cross bars 9 to move sufficiently thereon to cause the circuit between the contacts and said bars to be made and broken. The movement of these bars 9 is so slight that the holes therein need be only slightly elongated to provide an amplitude of movement to and fro sufficient to produce the results desired, and said cross bars serve as a means of support for the frame holders 9^c. Pivotedly mounted on the lower ends of these frame holders are locking bars 9^b, slotted at their upper ends and held, when in position, by wing nuts 9^e. The central locking bar 9^b is secured to the cross bars 9 with angles 9^d. The cams 6 are rigidly secured to the shaft 6^a which is revolvably mounted in bearings 6^b and are operated by chains 7 from motor 8. The hanger arms 5 have dependent arms 5^a which are held in continuous and slidable engagement by means of springs 5^c with cams 6.

The frame 3 is composed of upper and lower character block engaging channels 3^a, made rigid by having channels 3^b riveted to them, and bridged across by braces 3^c. The type or design blocks 10 have metallic projections 10^a. The blocks 10 are thrust the length of the channels until they strike pin 3^d which determines their proper position, and are secured to maintain their position, by means of clamp 11. The form-controlled switch board 2 is preferably made of insulating material, to which are secured the spring contacts 12 as shown in Figs. 1 and 3, and have preferably the identical geometrical arrangement as the sign board for each unit, three units being shown in Fig. 1, in which only a portion of the contacts are shown. The three units shown are connected in parallel with each other and the lamps on the sign board 1 are connected in series with the three units, the first row of lamps with the first row of contacts of each

key board unit, the second row of lamps with the second row of contacts, and so on as shown in Fig. 1.

Upon the frame 3^a is rigidly mounted 5 guides 3^b, which are adapted to facilitate the placing of said frame in the holder 9^a.

The operation is as follows: The switch 13 is thrown into engagement, which closes the circuit and operates motor 8, which 10 transmits motion to cams 6 by means of chains 7, which cam action in conjunction with compression springs 5^c reciprocates the frame 3 which contains a series of blocks 10, which throws them into and out of engagement with the spring contacts 12, thereby alternately making and breaking the electrical connection between the units and sign board. The intermittent operation of the several units with their respective frames of 15 character blocks in relation to each other, is controlled by the proper timing of the cams 6. The frames are grounded to cross bars 9 which are electrically connected to main circuit as shown in Fig. 1.

25 Though I have shown and described a particular construction and arrangement of parts, I do not wish to be limited to this particular construction and arrangement, but desire to include in the purview of my 30 invention, the construction and arrangement substantially as set forth in the appended claims.

Having thus described my invention, what I claim as new and desire to secure by Letters Patent is:—

35 1. In an electric sign, the combination with a form-controlled switch board provided with a series of electric contacts, of an open frame-holder parallel with and mounted to move toward and from said switch board, a frame adapted to be inserted into the frame-holder through one open side thereof, means for retaining the frame removably in its holder, and character blocks 40 inserted removably in said frame with their characters on their inner sides next to said contacts.

50 2. The combination with a switch board provided with a series of electric contacts on its outer face, of an open reciprocating frame-holder, means for moving the frame holder toward and from the contacts, an open frame mounted removably in the frame-holder, and character blocks mounted 55 removably in the frame with their characters exposed through the open sides of the frame-holder and frame for engagement with said contacts.

60 3. The combination with a switch board provided with a series of electric contacts on its outer side, of an open reciprocating frame-holder parallel with the outer side of the board supports on the board for the ends of the frame-holder holding it at all 65 times in parallelism with the board, means

for reciprocating the frame-holder, an open frame held removably in the said holder, and character blocks mounted removably in the said frame with their characters exposed through the open sides of the frame-holder and frame for engagement with the said contacts.

4. The combination with a switch board provided with a series of contacts, of an open frame-holder parallel with the board, 75 hangers hinged to the board and to the ends of the frame-holder to permit the latter to reciprocate in parallelism with the contact face of the board, a driven shaft parallel with the frame-holder and provided with cams engaging the hinged hangers to reciprocate the frame-holder, an open frame removably inserted into the frame holder through the outer open side thereof, means for retaining the frame in its holder, and character blocks removably mounted in said frame and removable therewith from the holder; the characters on the blocks being exposed through the open sides of the frame and the frame-holder for engagement with 80 the contacts.

5. The combination with a switch board provided with a series of contacts, of an open frame-holder, means for moving the frame-holder toward and from the contacts, 95 a removable open frame inserted in the frame-holder through the outer open side thereof and provided with upper and lower channels, and character blocks movable endwise into and out of said channels with their 100 characters exposed through the open sides of the frame-holder and frame for engagement with said contacts.

6. The combination with a switch board provided with a series of contacts, of an 105 open character block frame-holder parallel with the series of contacts and comprising upper and lower parallel bars, hangers hinged to the board at their outer ends and hinged at their inner ends to the ends of the frame-holder; said hangers having depending arms, springs pressing the frame-holder and hangers outwardly, and a rotary shaft having end cams engaging said depending arms.

110 7. The combination with an electric sign board bestudded with electric light bulbs, of a form controlled switch board having a plurality of groups of contacts electrically connected to said lights, a separate character block frame-holder parallel with every group of contacts, and mounted to move toward and from the respective groups of contacts, and gearing for successively actuating the said frame-holders.

115 8. The combination with an electric sign board bestudded with electric light bulbs, of a form-controlled switch board having a plurality of groups of contacts electrically connected to said lights, a separate character 120

block frame-holder parallel with every group of contacts, and mounted to move toward and from the respective groups of contacts, parallel shafts one for every frame-holder and provided with cams for actuating the same successively, and gearing connecting the said shafts.

9. In a form-controlled switch, a frame-holder open at front and rear, an open frame inserted in the said holder through its open front side and provided with upper and lower character block receiving channels, guides on the upper edge of the frame to assist in entering it in its holder, a stop

in one of the channels to limit the entrance 15 of the blocks therein, a movable stop at the other end of the channeled frame to hold the blocks therein, and retaining means on the frame-holder for securing the frame therein.

In testimony whereof, I have hereunto 20 subscribed my name in the presence of two subscribing witnesses.

ALBERT C. MEYER.
